UNITED STATES PATENT OFFICE.

ALLIE PONDER, OF EAST POINT, GEORGIA, ASSIGNOR TO COUCH BROS. MANUFACTURING CO., OF ATLANTA, GEORGIA, A CORPORATION OF GEORGIA.

BACK-BAND HOOK.

1,257,390.

Specification of Letters Patent.

Patented Feb. 26, 1918.

Application filed August 6, 1917. Serial No. 184,682.

To all whom it may concern:

Be it known that I, ALLIE PONDER, a citizen of the United States, and residing at East Point, Fulton county, State of Georgia, 5 have invented certain new and useful Improvements in Back-Band Hooks, of which the following is a specification.

This invention relates to buckles, particularly to buckles having hooks attached there- 10 to and used in connection with back bands, being known as back band hooks.

The object of the invention is to provide such a buckle which is of great strength and durability, yet which is simple, light in 15 weight, and easily manipulated.

The invention will be fully described in the following specification, taken in connection with the accompanying drawings, in which:—

20 Figure 1 is a front view of the buckle attached to a strip or band of fabric.

Fig. 2 is a plan view of the separated members of the buckle, and

25 Fig. 3 is a section along the line 3—3 of Fig. 1.

The body portion 10 of the buckle is in the shape of an elongated rectangle with a lateral extension on one side which supports the hook 11 adapted to hold the chain. This 30 hook is integral with the body portion 10 and is preferably formed by stamping up a portion thereof. The free end of the hook is in the plane of the body 10 and at or near the center of an opening 12 in the tongue, 35 which is considerably wider than the hook itself. This arrangement allows the link of a chain to be slipped over the hook, on which it is then held, with but little danger of its coming off.

40 The rectangular portion of the base 10 which comprises the buckle proper, has a long slot 13 therein along one edge of which is the upwardly extending flange 14. This flange is also integral with the base 10 and is 45 comprised of the material punched up therefrom when the slot is formed.

The ends of the slot and flange are diagonal, the upper edge of the flange extending beyond and overhanging the lower edge, and 50 the flange is inclined to the base with its upper edge overhanging the slot 13.

The bar 15 which co-operates with the base

10 to hold a strip of fabric A, is slightly longer than the flange and has lateral projections 16 at its ends which pass under the 55 overhanging or projecting portions 17 of the flange 14, and behind the flange, so that the bar cannot escape entirely from the body 10. Due to the manner in which it is secured thereto however, it has a limited motion to- 60 ward or from the body 10 and toward or from the flange 14, which allows a strip of fabric to be easily looped around the bar in attaching the device thereto.

In securing the buckle to a strip of fabric, 65 the end of the strip is passed from the back of the body 10, through slot 13, around the bar 15 and again passed out through slot 13. When weight is placed upon the hook 11, as when a trace chain is fastened thereon, the 70 strip of fabric tends to pull through the buckle. The pull of the fabric exerted against the back edge of the bar 15, over which it makes a sharp bend, forces the bar forward against that part of the strip of fabric passing 75 between its forward edge and the flange 14 and the strip is thus securely held, due to this clamping action, and due to the friction of the fabric against the bar at its back edge.

The forwardly extending portions 17 of 80 bar 15 prevent the bar from turning under the pull of the fabric.

To change the position of the buckle on the strip, for instance, to raise it, any desired length of the strip above the buckle is 85 passed through the slot from back to front and the loop thus formed in front is taken up by pulling on the strip below and in the rear of the buckle.

The buckle is strong yet light and easy to 90 make and because of the manner in which it frictionally holds the fabric without the aid of teeth, the fabric is not injured even when great weight is placed upon the hook.

Although I have shown and described my 95 invention in use as a back band hook, it may be used upon suspenders, or in other ways.

What I claim is:—

A buckle comprising a body portion hav- 100 ing a hook secured thereto and having a slot therein, a flange integral with said body portion and extending transversely therefrom along one edge of said slot, projections

on the ends of said flange, and a bar having lateral extensions passing around the ends of said flange under the projections thereon, whereby it is held to the base portion, the bar being movable through a limited distance toward or from said body portion and through a limited distance toward or from

said flange, said bar being adapted to co-operate with said body portion and said flange to frictionally engage a strip of fabric passing through said slot and looped around said bar. 10

In testimony whereof I affix my signature.
ALLIE PONDER.
